BUFFER MECHANISM FOR FIREARMS

Alonzo F. Gaidos, Redwood City, Calif., assignor
to the United States of America as represented
by the Secretary of War

Application January 10, 1947, Serial No. 721,332

9 Claims. (Cl. 89—198)

(Granted under the act of March 3, 1883, as
amended April 30, 1928; 370 O. G. 757)

1

The invention described herein may be manufactured and used by or for the Government for governmental purposes without the payment of royalty thereon.

This invention relates to a buffer mechanism for firearms, more particularly to a combination buffer mechanism and means for rapid detachment of the stock from the firearm, without disturbing the normal position of the buffer mechanism.

This invention essentially comprises a buffer arranged to be surrounded by the stock of the firearm and means for mounting the stock to the receiver of the firearm. The buffer mechanism comprises a tube slidably mounted within a housing member and a recoil spring contained within the tube to absorb the shock of the recoil forces. The housing in turn is secured to a backplate in such fashion that a ninety degree turn of the buffer mechanism will permit release thereof from the backplate. Detent means is provided to lock the stock to the backplate.

An object of this invention is to provide a combination buffer mechanism and stock mounting means for a firearm.

Another object of this invention is to provide a combination buffer and stock mounting means whereby the stock may be rapidly removed from the firearm, without disturbing the buffer mechanism.

The specific nature of the invention as well as other objects and advantages thereof will clearly appear from a description of a preferred embodiment as shown in the accompanying drawings in which:

Fig. 1 is a fragmentary longitudinal sectional view of the firearm showing the buffer mechanism in the normal position.

Fig. 2 is a similar view showing the actuator of the firearm in the recoil position against the buffer tube forcing such tube rearwardly to compress the recoil spring.

Fig. 3 is a cross-sectional view taken along the line 3—3 of Fig. 1.

Fig. 4 is a detail exploded perspective view showing the buffer mechanism housing with the backplate in position for assembly.

Fig. 5 is a detail side elevational view of the connector member.

Fig. 6 is a perspective view of the locking spring.

Fig. 7 is a fragmentary top elevational view showing the elements of the buffer mechanism assembled, but without the housing, disclosing

2

the manner in which the locking spring locks the various elements together.

In Fig. 2 there is shown in longitudinal section the firearm embodying this invention. Such firearm comprises mainly a receiver 1 having a bracket 14 at the rear end thereof and a butt stock 2 (Fig. 2). Receiver 1 houses a bolt 3, an actuator 4 and a firearm control mechanism 5. Fire control mechanism 5 is contained within a housing 16 having a pistol grip 67 and comprises a trigger 6, a sear member 7 having an upwardly projecting arm 8 adapted to engage actuator 4, as will be later explained, and a trigger spring 9. A safety 10 is provided to lock trigger 6 in a safe position. It is desired to point out here that fire control mechanism 5 is fully disclosed in my co-pending application Serial No. 694,443, filed Sept. 3, 1946, now Patent Number 2,482,758, hence need not be further described.

20 Bolt 3 is slidably contained within receiver 1 for longitudinal reciprocating movement. Bolt 3 includes a firing pin 11 which is actuated by a firing pin spring 12. An ejector 13 is provided in the head portion of bolt 3. A vertically disposed bolt stud 14 is provided on top of bolt 3 which engages a suitable cam track 15 in belt feed lever 25 journaled to pin 69 in top of receiver 1 to actuate the belt feed pawls of the firearm.

25 Actuator 4 is mounted in receiver 1 for reciprocating movement underneath and parallel to bolt 3. An upstanding vertically disposed lug 17 is provided on top of actuator 4 and such lug rests within a suitable notch 18 provided in firing pin 11 to effect actuation of firing pin 11. A longitudinal hole 19 is provided in actuator 4 to support

30 a guide rod 20 and a substantial part of hole 19 is counterbored to permit insertion of a driving spring 21 therein. The rear end of guide rod 20 is secured to the buffer mechanism in a manner as will be later described.

35 While the above forms no actual part of this invention being disclosed in the aforementioned application, however such is included herein as necessary to fully describe the operation and intent of this invention.

40 The combination buffer mechanism and stock securing means as indicated generally by the numeral 22 comprises a buffer tube 23, a buffer tube housing 24 and a hollow plug 31. Buffer tube housing 24 is a cylindrical member as shown in Figs. 1, 2 and 5 and an enlarged diameter head portion 26 is provided on one end thereof. On the small diameter portion of housing 24 there are provided a plurality of lugs 27, somewhat saw-

tooth in section, such lugs being annularly disposed about the periphery of housing 24. However, a substantial portion of such lugs 27 are removed as shown in Fig. 5 by splining to permit insertion of housing 24 into a backplate 28 to be presently described. An axial hole 29 is provided in housing 24 and the head portion 26 thereof is recessed and threaded as shown at 30.

Plug 31 is screwed into threaded recess 30 and such plug is provided with an integral hub 32 which acts as a spring guide. There is also an axial hole 33 in plug 31 which permits a reduced end portion of rod 20 to pass therethrough. Such rod is secured to the rear of plug 31 in a manner to be later described. Buffer tube 23 is a cylindrical member provided with an outwardly flared end 34, such end normally resting on the bottom of recess 30. When buffer tube 23 receives the impact of actuator 4 the flared end 34 of tube 23 is pushed rearwardly into the hollow interior of plug 31.

A helical buffer spring 36 is contained within buffer tube 23 such spring surrounding rod 20 and driving spring 21, one end being in abutment with plug 31, hub 32 supporting such end of the spring while the other end of spring 36 abuts the closed end of tube 23. An inwardly turned flange 37 is provided in the closed end of buffer tube 23 to permit passage of rod 20 therethrough.

Backplate 28 comprises a substantially rectangular plate 38 and a groove 39 is provided on opposite edges of plate 38 as shown in Fig. 4 to permit sliding such backplate onto suitable ribs (not shown) in receiver 1. An integral cylindrical boss-like member 40 is provided on the rear face of plate 38 and such boss is provided with oppositely disposed lugs 41 for a purpose to be presently described. Boss 40 is disposed at right angles to the rear surface of plate 38 and an axial hole 42 is provided therein extending through plate 38, such hole being provided with annular grooves 43 corresponding to lugs 27 on housing 24. Oppositely disposed splines 45 are provided in hole 42 to permit insertion of housing 24 into backplate 28 whereby such housing may be quickly secured to backplate 28 by a one-quarter turn thereof to engage lugs 27 with grooves 43 contained within backplate 28.

A cylindrical recess 46 (Fig. 1) is provided in the forward end of stock 2 on the axis thereof and is counterbored as shown at 47. A cylindrical housing member 48 provided with an enlarged head portion 49 is inserted in recess 46 and fits tightly within counterbore 47 to prevent such member from rotating. An axial hole 50 provided in housing 48 receives the buffer mechanism 22, which includes buffer tube 23, buffer housing 24 and plug 31. An annular groove 52 is provided in the interior of enlarged head portion 49 of housing 48 and oppositely disposed notches 51 are provided on the end face of head portion 49 to permit passage of lugs 41 of backplate 28 therethrough. A one-quarter turn of backplate 28 effects engagement of lugs 41 with annular groove 52 to secure such backplate to housing 48.

Housing 24 and plug 31 are preferably locked in a desired alignment to backplate 28 and such is accomplished by a locking member 53 comprising a substantially L-shaped spring-like member. A transverse hole 54 (Fig. 6) is provided in the vertically disposed leg 55 of locking member 53 and a slot communicating from the bottom of such leg to hole 54 is provided so that such leg may straddle an annular groove provided in the extreme rear end of rod 20. The other hori-

zontal leg of locking member 53 extends forwardly across the top of plug 31, housing 24 and backplate 28 lying within shallow longitudinal grooves 70, 71, and recess 72 provided in the top of each of the aforementioned members respectively. Thus these members are secured in proper alignment at all times which facilitates assembly and disassembly thereof from the firearm.

Detent means is provided to lock and position stock 2 to backplate 28. Such means comprises a spring 73 and a plunger 56 horizontally disposed within a suitable recess 57 provided on the top forward end of stock 2. A plurality of gear-like teeth 58 are provided on top of plunger 56 and such teeth cooperate with a pinion-like gear 59 supported by a transverse pin 60 within recess 57. The forward end of plunger 56 is of slightly reduced diameter and enters a hole 61 provided in backplate 28.

A plunger housing 62 is contained within recess 57 and abuts the rear surface of a stock ferrule 63 provided on the end of stock 2. A transverse hole 65 is provided in ferrule 63 to permit plunger 56 to pass therethrough and into hole 61 of backplate 28. Thus when plunger 56 projects through hole 65 into hole 61 of backplate 28, stock 2 is locked against rotational movement to receiver 1. Plunger 56 is readily retracted from hole 61 in backplate 28 by manual rotation of pinion 59.

With the buffer mechanism and stock assembled to the firearm as shown in Figs. 1 and 2, such buffer mechanism is set to receive the impact of actuator 4. In Fig. 2 the actuator is shown in contact with buffer tube 23 at the end of the recoil stroke. Buffer tube 23 has moved rearwardly a substantial amount thereby partially compressing spring 36 contained therein, thus absorbing a substantial part of the recoil forces. Driving spring 21 is likewise compressed on the recoil stroke of actuator 4. The forces exerted against spring 36 are in turn transmitted to backplate 28 by means of the connection of lugs 27 with backplate 28. At the completion of the recoil stroke of actuator 4, driving spring 21 and buffer spring 36 return actuator 4 forwardly whereupon sear arm 8 engages sear notch 66 provided in the underside of actuator 4. In such position, however, the buffer tube 23 no longer bears against the rear end surface of actuator 4.

Stock 2 is readily disassembled from receiver 1 by retracting plunger 56 by means of pinion 59, whereupon stock 2 may be rotated one-quarter of a turn in either direction so that lugs 41 come opposite notches 51 whereby the stock may be separated from receiver 1. If it is then desired to remove the buffer mechanism from backplate 28, locking member 53 is removed from engagement with rod 20 in order that buffer tube 23 and plug 31 may be rotated one-quarter of a turn to bring lugs 27 opposite the splined openings in backplate 28 whereupon such assembly is readily removed. Spring 36 is easily removed from tube 23 by unscrewing plug 31. It is obvious to those skilled in the art that assembly of such components is substantially in the reverse order of disassembly.

It is obvious therefore from the foregoing description and appended drawings that there is here provided a combination buffer mechanism and stock mounting means which is compact and provides for ease in assemblage of the firearm stock to the receiver whereby such firearm may be quickly taken down for inspection or for

transportation and a buffer mechanism that effectively cushions the recoil force of the reciprocating members of a firearm.

I claim:

1. In a firearm having a receiver, a reciprocating actuator member, a stock, a buffer mechanism comprising in combination, a backplate adapted to be slidably connected to the receiver, a spring biased buffer tube associated with said backplate being constructed and arranged to absorb the recoil force of the reciprocating actuator member, a housing recessed in the stock and adapted to surround said tube, means connecting said housing to said backplate, and detent means mounted in the stock and engageable with said backplate whereby the stock is locked to said backplate.

2. In a firearm having a receiver, a reciprocating actuator member, a stock and a buffer mechanism comprising in combination, a backplate adapted to be slidably connected to the receiver, a boss on said backplate, said boss and backplate being provided with a hole therethrough, a hollow housing member adapted to be inserted in said hole, means for releasably securing said housing within said hole, a buffer tube resiliently mounted for limited longitudinal movement within said housing whereby the recoil force of the reciprocating actuator member is absorbed when such member strikes the forward end of said tube, means for securing the stock to said backplate, and detent means mounted in the stock and engageable with said backplate whereby the stock is locked to said backplate.

3. In a firearm having a receiver, a reciprocating actuator member, a stock and a buffer mechanism comprising in combination, a backplate adapted to be slidably connected to the receiver, a boss on said backplate, said boss and backplate being provided with a splined hole therethrough, a plurality of spaced annularly disposed grooves on the unsplined portion of said hole, a hollow housing member adapted to be inserted in said splined hole, said housing having a plurality of annularly disposed lugs on the exterior thereof constructed and arranged to engage said grooves when said housing is partially rotated whereby said housing is secured within said splined hole, a buffer tube slidably mounted in said hollow housing, a recessed plug member secured to said housing, spring means associated with said tube and said plug member adapted to absorb the recoil force of the reciprocating actuator member, means for securing the stock to said backplate, and detent means mounted in the stock and engageable with said backplate whereby the stock is locked to said backplate.

4. In a firearm having a receiver, a reciprocating actuator member, a stock and a buffer mechanism comprising in combination, a backplate adapted to be slidably connected to the receiver, a boss on said backplate, said boss and backplate being provided with a hole therethrough, a hollow housing member adapted to be inserted in said hole, means for releasably securing said housing within said hole, a buffer tube slidably mounted for longitudinal movement within said housing, said tube having an outwardly flared end adapted to engage said housing, a recessed plug member secured to said housing, resilient means disposed within said tube and said plug member arranged to bias said tube forwardly whereby the recoil force of the reciprocating actuator member is absorbed when such member strikes the forward end of said

tube, means for securing the stock to said backplate, and detent means mounted in the stock and engageable with said backplate whereby the stock is locked to said backplate.

5. In a firearm having a receiver, a reciprocating actuator member, a stock and a buffer mechanism, comprising in combination, a backplate adapted to be slidably connected to the receiver, said back plate having a rearwardly disposed tubular member thereon and a hole therethrough to slidably receive a buffer tube housing, a radially disposed lug on the exterior of said tubular member, a hollow cylindrical housing recessed in the stock, said cylindrical housing having an enlarged cylindrical head portion, said head portion being provided with an interior annular groove and a slot on the face thereof adapted to receive said lug on said tubular member, a buffer tube slidably mounted in said buffer tube housing, a recessed plug member secured to the rear of said buffer tube housing, spring means associated with said tube and said plug member adapted to absorb the recoil force of the reciprocating actuator member, said backplate is locked to said cylindrical housing when said tubular member is inserted in said cylindrical housing and rotated thereby engaging said lug with said annular groove, and detent means mounted in the stock and engageable with said backplate whereby the stock is locked to said backplate.

6. In a firearm having a receiver, a reciprocating actuator member, a stock, and a buffer mechanism comprising in combination, a backplate adapted to be slidably connected to the receiver, said backplate having a rearwardly disposed tubular member thereon and a hole therethrough to slidably receive a buffer tube housing, a plurality of radially disposed lugs on the exterior of said tubular member, a hollow cylindrical housing recessed in the stock, said cylindrical housing having an enlarged cylindrical head portion, said head portion being provided with an interior annular groove and a slot on the face thereof adapted to receive said lugs on said tubular member, a buffer tube slidably mounted in said buffer tube housing, a recessed plug member secured to the rear of said buffer tube housing, spring means associated with said tube and said plug member adapted to absorb the recoil force of the reciprocating actuator member, said backplate is locked to said cylindrical housing when said tubular member is inserted in said cylindrical housing and rotated thereby engaging said lugs with said groove, and detent means mounted in the stock and engageable with said backplate whereby the stock is locked to said backplate.

7. In a firearm having a receiver, a reciprocating actuator member, a stock and a buffer mechanism comprising in combination, a backplate adapted to be slidably connected to the receiver, said backplate being provided with a hole therethrough, a hollow housing member adapted to be inserted in said hole, said housing having a recess therein, means for releasably securing said housing within said hole, a buffer tube slidably mounted for longitudinal movement within said housing, said tube having an outwardly flared end adapted to engage the bottom of said recess, a recessed plug member secured within said recess being constructed and arranged to limit the rearward movement of said tube, resilient means disposed within said tube and said plug member arranged to bias said

tube forwardly whereby the recoil force of the reciprocating actuator member is absorbed when such member strikes the forward end of said tube, locking means for locking said housing and plug to said backplate in a desired position, means for securing the stock to said backplate, and detent means mounted in the stock and engageable with said backplate whereby the stock is detachably locked to said backplate.

8. The combination defined in claim 7 wherein in said locking means comprises a leaf-like spring member having a depending portion, said depending portion being provided with a slot therein, said plug and housing being each provided with an exterior longitudinally disposed groove and said backplate having an exterior recess therein, said spring member adapted to lie in each of said grooves and to engage said recess when said grooves and recess are in alignment whereby said plug and housing are locked to said backplate, and a rod axially mounted within said tube and plug, said rod having an annular groove on the rear end thereof engageable with said slot in said depending portion to removably secure said leaf-like spring member thereto. 20

9. The combination defined in claim 5 where-

in said detent means comprises a plunger mounted within a recess in the stock, said plunger having a rack-like portion on the periphery thereof, a pinion mounted within said recess and engageable with said rack portion, and resilient means urging said plunger forwardly into engagement with said backplate whereby the stock is locked thereto, said pinion being provided to retract said plunger whereby the stock may be removed from said backplate.
